ATTY.

UNITED STATES PATENT OFFICE.

DOUGLAS WATSON SCOTT, OF NEWCASTLE-UPON-TYNE, ENGLAND, ASSIGNOR OF ONE HALF TO THOMAS CROW, OF NEWCASTLE-UPON-TYNE, ENGLAND.

DIRECTION INDICATOR.

1,406,501.

Specification of Letters Patent. Patented Feb. 14, 1922.

Application filed February 2, 1921. Serial No. 441,721.

To all whom it may concern:

Be it known that I, DOUGLAS WATSON SCOTT, a subject of the King of Great Britain and Ireland, residing at High West Jesmond, in the city and county of Newcastle-upon-Tyne, England, have invented new and useful Improvements in Direction Indicators, of which the following is a specification.

This invention relates to devices for indicating the intended direction of travel of a motor or other road vehicle, and which may also be used in a fixed position for directing and controlling traffic. The object of the invention is to provide an indicator of simple, economical and convenient construction.

In a direction indicator in accordance with the present invention a plurality of revolute shutters are mounted in front of a lamp and adapted to be simultaneously revolved in opposite directions to bring red and green glasses carried by said shutters into different relative positions whereby a single red light is shown in the normal position, and red and green lights are simultaneously shown when a turning to left or right is intended, the relative position of the lights indicating the direction of the intended turning.

My indicator is intended to constitute the regulation rear light of a vehicle, and at the same time indicate rearwardly the intended direction of travel of the vehicle.

In the accompanying drawings, Figure 1 is an elevation, partly in section, of a lamp fitted with one construction of my indicator; Figures 2, 3, 4 and 5 are front elevations of the housing, the back shutter, the front shutter, and the retaining ring, respectively; Figure 6 is an elevation, and Figure 7 is a sectional elevation, of the control. Figure 8 is a part similar view to Fig. 1; Figure 9 is a similar view to Fig. 3; and Figure 10 is a similar view to Fig. 4, illustrating a modified construction.

Referring first to Figs. 1 to 5, the indicator therein illustrated is substituted for the front glass of the lamp 11 (Fig. 1), and comprises two flat circular revolute shutters 12, 13 mounted in an annular housing 14 and retained therein by a flanged ring 15 which fits into the housing and is attached thereto by screws 16. Around the opposing faces of the shutters 12, 13 are provided teeth 17 which are engaged by interposed top and bottom pinions 18, 19 on a driving rod

20, the pinion 19 being attached to said rod by a screw 21, and the pinion 18 being loose on the rod and keeping the two shutters parallel. To the lower end of the rod 20 is attached the rear end of a flexible cable 22 protected by a flexible sheath 23. The rod 20 passes through apertures 24, 25 in the housing and through an aperture 26 in an axle 27 on which the shutters 11, 12 are mounted and revolve easily, said axle being carried by the radial arms 28 of the housing.

The back shutter 12 has an opening 29 covered by a green glass and two uncovered openings 30, 31 disposed diametrically opposite. The front shutter 13 has an opening 32 covered by a red glass and an uncovered opening 33.

The control illustrated in Figs. 6 and 7 comprises a revolute toothed wheel 34 mounted on a pin 35 carried by a base 36. The wheel 34, to which the control handle 37 and pointer 38 are attached, gears with the pinion 39 to which is attached the forward end of the flexible cable 22, said pinion being mounted in a bearing 40. Fitted to the base is a spring stop 41 adapted to engage one of three recesses 42, 43, 44 in the underside of the wheel 34 and hold the control when the pointer points to one of the words, Rear, Right or Left which are stamped on the base as shown.

The operation of the above described indicator is as follows:—The shutters 12, 13 are set so that the red glass 32 coincides with the opening 30. In this, the normal, position the red glass alone is illuminated by the lamp 11, and the indicator performs the functions of the regulation rear light. The pointer 38 of the control points to Rear when the shutters are in the normal position. When the wheel 34 is revolved in the clockwise direction to bring the pointer opposite to Right, the rotation is transmitted by the pinion 39, cable 22, rod 20 and pinion 19 to the shutters 12, 13 which are thereby revolved in opposite directions until a stop 45 on the front shutter 13 strikes a stop 46 on the retaining ring 15 in which position the green glass 29 coincides with the opening 33 and the red glass 32 coincides with the opening 31 thus simultaneously showing red and green lights, the red on the right and the green on the left, to indicate an intended turning of the vehicle to the right. Conversely, the counter-clockwise rotation of the

wheel 34 to bring the pointer 38 opposite to Left will revolve the shutters 12, 13 in opposite directions until the stop 45 strikes a stop 47 on the ring 15, in which position the 5 green glass 29 coincides with the opening 33 and the red glass coincides with the opening 31 thus simultaneously showing red and green lights but with the red on the left and the green on the right to indicate an intended 10 turning to the left.

In the modified construction illustrated in Figs. 8, 9 and 10, the opening 32 covered by the red glass is central of the back shutter 12, the green glass 29 being also mounted in 15 the back shutter, as shown in Fig. 9. In the front shutter 13 (Fig. 10) are two uncovered openings, one 48 being central and coinciding with the red glass, and the other 49 co-acting with the green glass. The modified 20 shutters are oppositely revolved in the manner above described when the control is moved, and provide a permanent red rear light, the green light being obscured or shown to right or to left of the red light according 25 to the intended direction of the vehicle. Between the two shutters is an annular projection 50 which keeps the shutters parallel. The projection is shown attached to the rear face of the front shutter, but may be attached to either shutter. The driving rod 20 is cut above the pinion 19, and the pinion 18 and the axle 27 and arms 28 of the housing 30 14 are all dispensed with.

A signal arm 51 (Figs. 8 and 10) is attached to the front shutter 13 to indicate the intended direction of the vehicle during the daytime when the lamp 11 is not lit.

What I claim as my invention and desire to secure by Letters Patent is:—

- 40 1. A direction indicator comprising the combination of a lamp, a plurality of revoluble shutters having coloured glasses and openings, means for mounting said shutters in front of said lamp, and means for simultaneously revolving said shutters in opposite directions to bring their coloured glasses into different relative positions.
- 45 2. A direction indicator comprising the combination of a lamp, an annular housing in front of said lamp, a plurality of flat circular shutters revolubly mounted in said housing, said shutters having coloured glasses and openings, a flanged ring for retaining said shutters in said housing, and means for simultaneously revolving said shutters in opposite directions to bring their

coloured glasses into different relative positions.

3. A direction indicator comprising the combination of a lamp, an annular housing 60 in front of said lamp, a plurality of flat circular shutters revolubly mounted in said housing, said shutters having coloured glasses and openings, a flanged ring for retaining said shutters in said housing, teeth 65 around the opposing faces of said shutters, a pinion interposed between said shutters engaging said teeth, and means for rotating said pinion to simultaneously revolve said shutters in opposite directions to bring their 70 coloured glasses into different relative positions.

4. A direction indicator comprising the combination of a lamp, an annular housing 75 in front of said lamp, a plurality of flat circular shutters revolubly mounted in said housing, said shutters having coloured glasses and openings, a flanged ring for retaining said shutters in said housing, teeth around the opposing faces of said shutters, 80 a pinion interposed between said shutters engaging said teeth, a flexible cable one end of which is connected to said pinion, a flexible sheath for said cable, and means for rotating said flexible cable to simultaneously 85 revolve said shutters in opposite directions to bring their coloured glasses into different relative positions.

5. A direction indicator comprising the combination of a lamp, an annular housing 90 in front of said lamp, a plurality of flat circular shutters revolubly mounted in said housing, said shutters having coloured glasses and openings, a flanged ring for retaining said shutters in said housing, teeth 95 around the opposing faces of said shutters, a pinion interposed between said shutters engaging said teeth, a flexible cable one end of which is connected to said pinion, a flexible sheath for said cable, a pinion on the 100 other end of said cable, a toothed wheel rotating said pinion, means for supporting said toothed wheel and pinion, a pointer on said toothed wheel, an indicator over which said pointer works, and means for rotating 105 said toothed wheel to simultaneously revolve said shutters in opposite directions to bring their coloured glasses into different relative positions.

In testimony whereof I have signed my 110 name to this specification.

DOUGLAS WATSON SCOTT.
